UNITED STATES PATENT OFFICE.

GUY A. TOBEY AND WILLIAM A. FLOWER, OF TWIN FALLS, IDAHO.

PHOTOGRAPHIC-PRINTING MASK.

1,182,060.

Specification of Letters Patent. Patented May 9, 1916.

Application filed October 2, 1915. Serial No. 53,810.

To all whom it may concern:

Be it known that we, GUY A. TOBEY and WILLIAM A. FLOWER, citizens of the United States, residing at Twin Falls, in the county 5 of Twin Falls, State of Idaho, have invented a new and useful Photographic-Printing Mask, of which the following is a specification.

The present invention appertains to 10 photographic printing masks, and aims to provide a mask of that character provided with novel means whereby various numbers or identification marks may be provided upon the margins of the prints during 15 the printing operation, whereby the prints after being fixed, washed and dried can be readily sorted without the necessity of comparing the prints with the negatives as customary.

20 It is the prevailing practice in making prints from negatives to fix, wash, dry and trim the prints altogether, which requires the various groups or jobs to be assorted by comparing the prints with the negatives, 25 and which involves more or less confusion and trouble. With the present mask, each group of prints or job has an individual number or identification mark provided upon the prints at the time of the exposure 30 thereof, so that when the prints have been washed and dried, they can be readily assorted simply by using the identification numbers or marks, these identification numbers or marks being cut off when the prints 35 are trimmed.

Another object of the invention is the provision of a photographic printing mask of the nature specified, whereby the identification number or mark to be provided 40 upon the print can be changed readily, so that various jobs can be assigned different numbers or marks.

It is also within the scope of the invention to provide an improved mask having the 45 above characteristics, and which at the same time is simple and inexpensive in construction, which can be used in ordinary printing frames and machines, and which is practical, convenient, serviceable and efficient in use.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:

Figure 1 is a plan view of one form of mask. Fig. 2 is a section thereof taken on the line 2—2 of Fig. 1. Fig. 3 is a plan view of another form of mask. Fig. 4 is a section on the line 4—4 of Fig. 3. Fig. 5 is a plan view of a second modification. Fig. 6 is a section on the line 6—6 of Fig. 5.

In carrying out the invention, reference being had particularly to Figs. 1 and 2, there is provided a mask 1 of any suitable size and contour, and having a suitable opening 2 through which the sensitized paper is exposed, this mask being applied to the negative and sensitized paper in the ordinary manner, either in a printing frame or a printing machine. The mask 1 may be of opaque material or may be of amber colored 75 semi-transparent material so as to prevent the actinic light rays from penetrating the mask but to allow the non-actinic rays to pass through the mask for purpose of convenience in using the mask.

In carrying out the invention, the mask 1 is provided at one side or adjacent one edge of the opening 2 with two pairs of parallel slits 3 forming bridging portions or straps 4 suitably spaced apart. The mask 1 is 90 also provided with a suitable aperture 5 between the straps 4. A strip 6, preferably of the same material as the mask 1, is disposed slidably upon the mask and passes slidably under the straps 4 which are offset from the body of the mask to guide the strip 6 for longitudinal movement, the ends of the strips 6 protruding from the straps 4 to allow the strip to be slid or adjusted longitudinally by the fingers. This strip 6 has a 100

longitudinal series of identification numbers or marks 7 formed by slotting or perforating the strip to allow the light rays to pass through the slots or perforations. One number or mark 7 can be brought into register with the aperture 5 and by moving the strip 6 longitudinally the numbers can be moved in succession over the aperture 5, whereby various jobs or sets of prints can be allotted 10 different numbers or marks. Opaque pasters or elements 8 are pasted or otherwise secured to that side of the mask 1 opposite the straps 4, to close the slits 3, and to also reinforce the mask 1 where it is slotted.

15 When one set of prints is being made, the strip 6 is adjusted to bring the selected number or mark 7 over the aperture 5, and then when the sensitized paper is exposed, the light rays will pass through the identification number over the aperture 5 and through the aperture, but the mask will close the other identification numbers. The proper identification number is thus printed upon the sensitized paper at the margin of 20 the print. When a new job is taken up, the strip 6 is shifted to bring a new identification number over the aperture 5. When the several strips of prints are fixed, washed and dried in a mixed condition, they 25 can be readily assorted by means of the identification marks, and without the necessity of comparing the prints with the negatives as usual. This saves considerable time and trouble. The identification marks are 30 provided upon the sensitized paper at the same time that the paper is exposed for purpose of printing, so that the present invention will not involve additional work, it only being necessary to adjust the strip 6 35 when the new jobs are taken up.

The second form of the invention illustrated in Figs. 3 and 4 is used for the same purpose, but is of slightly different construction. The mask 11 which is provided 40 with the opening 12 has a pair of slits 13 at one side of the opening 12, and preferably parallel with the respective edge of the opening. These slits 13 provide a bridging portion or strap 14, and a pair of disks 16 45 are disposed upon the body portion of the mask 11 under the strap 14, said strap holding the disks against the body of the mask.

The mask 11 is provided with an aperture 5 for each disk 16 over which the marginal portion of the disks or disk project, the marginal portion of each disk having an annular series of identification numbers or marks 17 formed by slotting or perforating the disk to allow the light rays to pass 50 through the perforated or slotted portions. The disks 16 are mounted for rotation between the body of the mask and the strap 14 by means of rivets or other pivot elements 18 engaged through the centers of

the disks and the straps 14. The disks 16 65 are preferably overlapped to bring them closer together. The mask 11 and disks 16 may be constructed of the same materials as the mask 1 and strip 6, and any suitable number of disks 16 may be employed according to the number of jobs which are liable to require completion at the same time. Each disk has identification numbers running from 0 to 9, and each disk also has a blank portion adapted to be moved over 70 the respective aperture 15 for preventing the light from passing through the aperture, and with the two disks 16, it is possible to use identification numbers from 0 to 99, by properly rotating the disks as will 75 be apparent without detailed description.

In the variation illustrated in Figs. 5 and 6, the identification numbers or marks are provided in the mask itself, while the movable member carried by the mask is provided with the aperture. The mask 21 has the opening 22, and opposite pairs of slits 23 at one side of said opening providing the straps or bridging portions 24 through which a pair of parallel strips 26 are slid- 80 able. The strips and mask are constructed of the same materials as the masks and movable parts carried thereby above described, the strips 26 being disposed upon the mask and passing under the straps 24. The identification numbers or marks 27 are provided in the mask 21 between the pairs of slits 23, and each of the strips 26 is provided with an aperture 25 between the straps 24. By moving the strips 26, the apertures 25 may 85 be brought over the desired identification numbers, while the others are closed. This is a reversal of the structure disclosed in 90 Figs. 1 and 2, and its utility will be readily understood from the foregoing.

Having thus described the invention, what is claimed as new is:

1. A photographic printing mask having an aperture and having a pair of slits providing a strap, and a movable member disposed between the body of the mask and said strap to move across said aperture, said member having a series of identification mark providing portions movable in succession over said aperture.

2. A photographic printing mask, and a movable member disposed thereon, one of said parts having a series of identification mark providing portions and the other having an aperture for exposing said portions in succession, the mask having a pair of slits providing a strap and the movable member being disposed between the body of the mask and said strap to hold it in place.

3. A photographic printing mask, and a movable member disposed thereon, one of said parts having a series of identification

mark providing portions and the other having an aperture for exposing said portions in succession, the mask having a strap, and said movable member being disposed between said strap and the body of the mask to be held in place against the mask by the strap.

In testimony that we claim the foregoing

as our own, we have hereto affixed our signatures in the presence of two witnesses. 10

GUY A. TOBEY.
WILLIAM A. FLOWER.
